UNITED STATES PATENT OFFICE

FRANK E. KNEELAND, OF CHICAGO, ILLINOIS, ASSIGNOR TO SAFETY MINING COMPANY, OF CHICAGO, ILLINOIS, A CORPORATION

BLASTING CARTRIDGE

Application filed November 29, 1929. Serial No. 410,629.

The present invention is concerned with certain improvements in blasting cartridges of the type wherein the blasting medium is a highly compressed or liquefied gas and wherein an electrically energizable heater unit is employed to bring about the blasting pressure.

It is an object of the invention to simplify and render more reliable those parts of such a cartridge having to do with the introduction of the blasting medium and the establishment of the necessary electrical connections for the heater unit.

More particularly, it is an object of the invention to provide separate valve and electrode units, each of simple and efficient design.

Another of the more particular objects of the invention is to provide a cartridge so constructed internally as to automatically and positively guide an inserted heater unit into contact with an electrode.

Referring to the drawings,

Figure 1 is a view in longitudinal section through a portion of a blasting cartridge embodying the improvements of the present invention.

Figure 2 is a view in transverse section along line 2—2 of Figure 1.

Figures 3 and 4 are views in longitudinal section and end elevation, respectively, of the terminal plug shown in dotted outline in Figure 1.

A blasting cartridge of the general type with which this invention is concerned is illustrated in the Ferrell et al. Patent No. 1,610,274. This type of cartridge consists of a metallic body having an internal gas chamber, the open end of which is adapted to be closed by a pressure responsive rupturable disc or other suitable form of pressure responsive venting means. The opposite end of the cartridge body is provided with an electrode and a charging valve, both having communication with the gas chamber. In order to bring about the desired blasting pressure of the gaseous charge there is provided an electrically energizable heater unit, which extends between and has contact at its opposite ends with the electrode and rup-

turable disc respectively. In operation, the heater unit is inserted in the gas chamber and placed in electrical contact with the electrode following which the discharge assembly is applied to the end of the cartridge and so adjusted with respect thereto that the discharge opening is effectively sealed against the escape of gas. With the cartridge thus conditioned, a charge of the blasting medium may be introduced into the chamber through the adjustable charging valve. After the cartridge has been thus charged and transported to the place where it is to be discharged, it is merely necessary to connect the leads from a source of electricity to the electrode and cartridge body respectively in order to energize the heater and thereby increase the pressure of the charge up to the blasting pressure, at which point the disc or other form of venting means will liberate the charge to do its work.

The present construction includes a substantially cylindrical metallic body 1 having a gas chamber 2 of suitable capacity for the work to be done. One end of the body is provided with a discharge opening which is in communication with the interior of the gas chamber and this opening is designed to be sealed by any suitable form of pressure responsive venting device. This discharge end of the cartridge has not been illustrated herein since it forms no part of the present invention. The opposite end of the cartridge body is provided with separate valve and electrode elements 3 and 4 respectively.

Heretofore it has been common practice to construct the valve and electrode elements as a combined unit. One form of such a combined valve and electrode unit is illustrated in the above mentioned patent. According to the present construction, however, the valve and electrode are constructed and mounted as entirely separate and independent units. This change gives rise to a very advantageous simplification of both the valve and electrode units and makes possible a far more efficient and reliable electrode and electrode mounting. As shown in the drawings, the electrode 3 is provided with an intermediate enlarged portion 5 and a reduced portion 6 which ex-

tends into the gas chamber. An insulating sleeve 7 surrounds the portion of the electrode 6 at the point where it passes through the end wall of the gas chamber. Interposed between the outer surface of the end wall of the gas chamber and the adjacent radial face of the enlarged portions 5 of the electrode is an insulating and sealing disc 8. The periphery of the enlarged portion 5 is likewise insulated from the body of the cartridge by means of an annular band 9 formed of insulating material. The outer end of the electrode is surrounded by an insulating sleeve 10 and on this sleeve there is positioned an electrode nut 11 which has threaded engagement with the body of the cartridge. The enlarged portion 5 of the electrode is separated from the electrode nut 11 by means of an insulating disc 12. The electrode nut 11 acts against the outer face of the enlarged portion 5 of the electrode surface to exert a sealing pressure between the opposite face of the enlarged portion of the electrode and the adjacent surface of the cartridge body through the medium of the disc 8. It will be noted that portion 6 of the electrode which extends into the gas chamber is of extremely small cross sectional area as compared with the type of electrode heretofore employed in combination with a valve. It is also to be noted that the enlarged portion 5 of the electrode affords a comparatively large area on which to effect the sealing between the electrode and the body of the cartridge. Thus, owing to the extremely small cross sectional area of that portion of the electrode which is exposed to the pressure within the gas chamber and the relation of this area to the area of the surface on which the sealing is effected, it is apparent that the 40 extremely high pressures which exist in cartridges of this type at the time of discharge will not seriously affect the condition of the present electrode assembly.

The valve 4 is provided with a substantially conical end which extends into a small chamber 15 formed in the body of the cartridge. This chamber is in communication with a charging orifice 15 and a passage 14, the latter of which has communication with the gas chamber. The valve has threaded connection with the body of the cartridge as indicated at 16 in order that the conical end thereof may be adjusted toward and from sealing position with respect to the outer end 55 of the passage 14. A packing gland 17 is provided to prevent the escape of gas around the valve unit.

Another important feature of the present construction is the design of the interior of the gas chamber adjacent the electrode. The end of the gas chamber 2 is formed as indicated at 18 so that the walls thereof converge toward the electrode. The function of this design is to facilitate the entry of a heater unit 65 and to insure the establishment of contact

between an end of the unit and the inner end of the electrode. According to current practice, these heater units consist of an elongated paper tube having metallic end closures which are connected to the leads of an electric matchhead disposed within the tube. The tube is filled with a suitable heat producing mixture capable of being energized by the ignition of an electric matchhead. In using such a heater with the present cartridge it is merely necessary to insert the same through the discharge end of the cartridge, after which the discharge assembly may be secured in position. The heater unit will automatically become centered and establish contact with the electrode by virtue of the conical formation of the interior of the gas chamber.

The valve and electrode units may be protected by a cap 19 having threaded engagement with the end of the cartridge body. This cap is preferably provided with a central opening 20 for the reception of a terminal plug and one or more openings 21 in which an electric conductor may be secured.

The terminal plug 22 may be of any suitable form capable of being passed through the opening 20 of the cap and engaging and forming electrical connection with the outer end of the electrode. As herein shown, the plug consists of a metallic body 23, one end of which is formed with a plurality of resilient contact fingers 24. The body is surrounded by an insulating sleeve 25 to prevent contact thereof with the metallic protector cap and the plug assembly is completed by a cap member 26 surrounding the outer end of the insulating body 25. The outer end of the body 23 may be belled out as indicated at 27 to secure the several parts of the plug in assembled relation.

I claim:

1. In a blasting cartridge of the type comprising a substantially cylindrical metallic body having an internal fluid chamber with a discharge opening in one end thereof, the combination of an insulated electrode positioned in the opposite end of said body and extending into said chamber, and an inclined approach to said electrode, whereby a heater unit inserted in said fluid chamber may be automatically guided into position to establish contact with said electrode.

2. In a blasting cartridge of the type comprising a substantially cylindrical metallic body having an internal fluid chamber with a discharge opening in one end thereof, the opposite end of said body having a bore of relatively small diameter communicating with the interior of said fluid chamber and a pocket of relatively large diameter outwardly of and substantially concentric with said bore, an electrode having a portion of relatively small diameter adapted to extend thru said bore and into said chamber and a portion of

relatively large diameter adapted to be positioned within said pocket, means for insulating said electrode from said body, and a nut having threaded engagement with said pocket for exerting pressure on said electrode.

Signed at Chicago, Illinois, this 19th day of November, 1929.

FRANK H. KNEELAND.
